UNITED STATES PATENT OFFICE.

JOHN MOLES, OF ERIE, PENNSYLVANIA, ASSIGNOR TO THE EUREKA COMPANY, OF NORTH EAST, PENNSYLVANIA, A CORPORATION OF PENNSYLVANIA.

COMMUTATOR-TURNING TOOL.

1,158,532.

Specification of Letters Patent.

Patented Nov. 2, 1915.

Application filed July 24, 1915. Serial No. 41,691.

To all whom it may concern:

Be it known that I, JOHN MOLES, a citizen of the United States, residing at Erie, in the county of Erie and State of Pennsylvania, have invented new and useful Improvements in Commutator-Turning Tools, of which the following is a specification.

This invention relates to commutator turning tools and consists in certain improvements in the construction thereof as will be hereinafter fully described and pointed out in the claims.

In the turning of commutator bars it has been the practice to assemble these bars with insulating material between them in their final annular position and to clamp the bars so assembled so that the surfaces of the bars may be turned. The ordinary commutator bars have the insides of the bars turned and are also provided with anchor parts which with the bars assembled form a dove-tail ring on the inner periphery of the commutator. Difficulty has been experienced in turning the insides of the bars and the beveled surfaces of these anchor parts with rapidity.

The object of this invention is to accomplish this purpose in a better manner than has been heretofore practised and to provide the tool for so accomplishing the purpose.

The invention is illustrated in the accompanying drawing wherein 1 marks the shank of the tool, 2 the tool holder, and 3 a first tool which is secured to the tool holder by extending into the tool holder and being clamped therein by set screws 4.

5 is a second tool extending into the tool holder and being clamped therein by set screws 6.

7 is a stop for limiting the axial movement of the tool relatively to the commutator, this stop extending into the tool holder and being clamped therein by a set screw 9. The first tool 3 has a cutting edge 10 which is adapted to turn the inner surface 11^a of the bars 11. The tool must have a clearance sufficient to avoid cutting the face of the anchor part 13 because if the rear of the back edge of the tool engages the anchor part it crowds the tool so as to produce inaccuracies in the diameter of the inner surfaces 11^a. The tool 5 has a cutting face 12 which is designed to cut the beveled

face of the anchor pieces 13. This tool 55 should have clearance enough to avoid cutting the surface 11^a so that the accuracy of the cutting device 12 is not interfered with. In this way the two surfaces, the face of the anchor parts and the surface 11^a may be cut 60 with great rapidity and with great accuracy. The sharp groove such as is formed by the commutator bars between the inner surface of the commutator and the anchor pieces presents great difficulty even where the material turned is solid but where there is a variation as in commutator bars and their insulating material the difficulty precludes ordinary methods and the operation has been heretofore very slow.

A tool 14 is carried by an extension 15 on the shank 1 and secured in place by the set screws 16. This is designed to operate in advance of the tools 3 and 5 and to turn the inner surfaces of the anchor parts.

It will be readily observed that the ends of the tools 3 and 5 are practically in a plane at right angles to the axis of the tool. This is necessary in order that the tool 5 may be utilized only for cutting the surfaces of the anchor parts and the tool 3 for the inner surfaces of the bars.

What I claim as new is:—

1. In a commutator turning tool, the combination of a shank; and cutting tools carried by the shank, the first of said tools having a cutting edge extending in an axial direction to turn the inner surfaces of assembled commutator bars, the end of said first tool having a clearance to avoid cutting the anchor part of such bars, and the second of said tools having a cutting edge extending on a slant to the axis of the tool to form the face of the anchor part of the bars and having a clearance to avoid cutting the inner surface of the bars, the ends of said tools being in a plane at right angles to the axis.

2. In a commutator turning tool, the combination of a shank; cutting tools carried by the shank, the first of said tools having a cutting edge extending in an axial direction to turn the inner surfaces of assembled commutator bars, the end of said first tool having a clearance to avoid cutting the anchor part of such bars, and the second of said tools having a cutting edge extending on a slant to the axis of the tool to form

the face of the anchor part of the bars and having a clearance to avoid cutting the inner surface of the bars, the ends of said tools being in a plane at right angles to the axis; and a third tool in advance of the first and second tools for turning the inner surface of the anchor part of the bars.

In testimony whereof I have hereunto set my hand in the presence of two subscribing witnesses.

JOHN MOLES.
